CLAIM

The ornamental design for a protective vacuum shield for personal service providers, as shown and described.

DESCRIPTION

FIG. 1 is a top perspective view of a protective vacuum shield for personal service providers according to our new design;

FIG. 2 is a bottom perspective view thereof;

FIG. 3 is a front view thereof;

FIG. 4 is a back view thereof;

FIG. 5 is a side view thereof;

FIG. 6 is an opposite side view thereof;

FIG. 7 is a top view thereof; and,

FIG. 8 is a bottom view thereof.

The broken lines in the drawings depict environmental subject matter and form no part of the claimed design.
